UNITED STATES PATENT OFFICE

JAMES W. KELCH AND JAMES J. SUNDAY, OF DETROIT, MICHIGAN, ASSIGNEES, BY
DIRECT AND MESNE ASSIGNMENTS, TO KELCH VENTILATING HEATER COMPANY, A
CORPORATION OF MICHIGAN

COMBINED HEATER AND MUFFLER FOR AUTOMOBILES

Application filed December 31, 1925. Serial No. 73,635.

This invention relates generally to heaters for automobiles and the like and consists of certain novel features of construction, combinations and arrangements of parts as will be more fully described and particularly pointed out in the appended claims.

In the accompanying drawings:

Figure 1 is a fragmentary side elevation of a vehicle body with a heater embodying our invention applied thereto.

Figure 2 is an enlarged vertical longitudinal sectional view through the heater.

Figure 3 is an end elevation of the core.

Figure 4 is a view similar to Figure 2 showing a slight modification.

Figure 5 is a longitudinally vertical sectional view through a slightly modified form of heater.

Figure 6 is a longitudinally vertical sectional view through another modified form of construction.

Figure 7 is a view similar to Figure 6 but showing another modified form.

Referring now to the drawings, the numeral 1 designates a heater for automobiles and the like having a core 2 and an outer shell or casting 3. As shown, this core preferably comprises a plurality of straight tubes 4 and their supporting plates 5 and 6 respectively, while the shell 3 preferably comprises the tubular body 7 and the funnel-shaped headers 8 and 9 respectively. To provide an efficient construction, the plates 5 and 6 of the core are preferably provided with marginal flanges 10 and 11 respectively which fit snugly within the tubular body 7 at the opposite ends thereof, while the flared portions of the headers 8 and 9 are preferably provided with annular flanges 12 and 13 respectively which fits snugly within the marginal flanges 10 and 11.

In order that the exhaust gases from the engine of the vehicle may be used as the heating medium, the forward header 8 is connected to the usual exhaust conduit 14 of the vehicle. Any suitable means may be employed for conveying air from the atmosphere to the tubular body 7 and from the shell to the body 15 of the vehicle. As shown, a supply pipe 16 extends forwardly from the tubular

body 7 adjacent to the header 8 and terminates in a flared portion 17, preferably immediately in rear of the usual fan 18 of the engine, while a pipe 19 extends rearwardly from the tubular body 7 adjacent to the header 9 and connects into a suitable air register 20 located preferably in the floor 21 of the vehicle body.

As shown in Figures 2 and 3 of the drawings, the tubes 4 are preferably arranged close together to provide in effect a common passage for the gases through the shell and are provided at their forward ends in advance of the plate 5 with flared portions 22 which are welded together. Thus, the tubes 4 are in substantial alignment with the exhaust inlet 23 and the integrated portions 22 of the tubes are constructed and arranged in such a way as to form a header which will distribute uniformly the exhaust gases directly into the tubes, hence the maximum heat will be obtained. Moreover the arrangement is such that the gases will have a free and unobstructed stream line flow through the shell so as not to cause back pressure on the motor.

In the process of construction, the heater is formed by first inserting the tubes 4 through suitable apertures in the plates 5 and 6 respectively; second, welding together the flared ends 22 of the tubes; third, welding the tubes to the plates 5 and 6; fourth, welding the headers 8 and 9 to the flanges 10 and 11; fifth, slipping the tubular body 7 upon the flanges 10 and 11; and finally, welding one end only, preferably the forward end of the tubular body 7 to the flange 10 and header 8. Thus a sliding joint is provided at the opposite end of the heater between the tubular body 7 and the flange 11 to take care of expansion and contraction of the core. Inasmuch as the tubes 4 are welded together and are welded to the plates 5 and 6 it will also be apparent that the rigid joints so provided will reinforce the walls of both the shell and tubes and will prevent the parts from vibrating or rattling.

In Figure 4 we have shown a slight modification in which the tubular body 7 is secured to the flanges 10 and 11 by means of tongues 24. As shown, the tubular body 7 is pro-

vided at its opposite ends with elongated slots 25 that receive the tongues 24. In the process of construction, the tubular body 7 is sleeved upon the flanges 10 and 11 with the slots 25 in position to receive the tongues 24. These tongues are then bent back over the inner ends of the slots 25 to secure the parts together. Thus the tubular body 7 has a sliding engagement with both flanges 10 and 11 to take care of expansion and contraction of the core.

In Figure 5 we have shown another modification in which a heater and muffler are combined in one unit. As shown, a perforated cone-shaped baffle 30 has a marginal flange 31 secured to the flared portion of the forward header 8 and projects rearwardly toward the center tube of the core, while coaxially arranged apertured baffles 32 and 33 respectively have marginal flanges 34 and 35 secured to the flared portion of the rear header 9 and preferably project rearwardly toward the exhaust outlet 36. In use, the exhaust gases entering the header 8 will pass through the perforations in the baffle 30 in small streams which will flow into the tubes 4 and then outwardly through the perforations in the baffles 32 and 33 to the exhaust outlet 36. Thus it will be apparent that the apertures in the baffles will permit the gases to flow freely through the shell so as not to cause objectionable back pressure on the engine and will serve effectively to deaden the sound of exhaust into the air so as to render such sound unobjectionable.

In Figure 6 we have shown another modification in which the forward baffle 40 is provided with longitudinally spaced annular shoulders 41 which have apertures 42 therein through which the gases may flow directly into the tubes 4.

In Figure 7 we have shown still another modification in which the forward baffle 50 is provided with apertures 51 to permit the ready passage of the exhaust gases and is preferably provided at the rear edges of the apertures with rearwardly extending tongues 52 which serve to direct the exhaust streams from the apertures toward the tubes 4.

While it is believed that from the foregoing description, the nature and advantage of our invention will be readily apparent, we desire to have it understood that we do not limit ourselves to what is herein shown and described and that such changes may be resorted to when desired as fall within the scope of what is claimed.

What we claim as our invention is:

1. A combined heater and muffler including a casing having substantially aligned inlet and outlet ports for exhaust gases, a plurality of tubes extending longitudinally of the casing between said ports, and a baffle in advance of said tubes having perforations

through which said gases may flow into said tubes.

2. A combined heater and muffler including a casing having substantially aligned inlet and outlet ports for exhaust gases, a plurality of tubes extending longitudinally of the casing between said ports, and a baffle of conical configuration projecting toward the tubes having perforations through which said gases may flow directly into said tubes. 70

3. A combined heater and muffler including a casing having substantially aligned inlet and outlet ports for exhaust gases, a plurality of tubes extending longitudinally of the casing between said ports and a baffle in advance of said tubes having perforations through which said gases may flow, said baffle being so constructed and arranged as to cause the gases passing through said perforations to flow in straight lines from said perforations into said tubes. 80

4. A combined heater and muffler including a casing having substantially aligned inlet and outlet ports for exhaust gases, a plurality of tubes extending longitudinally of the casing between said ports, and a baffle in advance of said tubes having perforations through which said gases may flow, said perforations being provided with rearwardly extending tongues for directing the flow of gases into said tubes. 90

5. A combined heater and muffler including a casing having substantially aligned inlet and outlet ports for exhaust gases, a plurality of tubes extending longitudinally of the casing between said ports, and a baffle of conical configuration projecting toward the tubes having perforations through which said gases may flow, said perforations being provided with rearwardly extending tongues arranged in parallel relation to one another for directing the flow of gases directly into said tubes. 100

6. A heater for automobile bodies comprising a shell having a tubular body, tubes within the shell, forward and rear supporting plates for said tubes, said tubes projecting through said forward plate and being provided in advance thereof with cooperating deflecting means for the exhaust gases, and means separate from and in advance of said forward plate for deflecting gases toward the deflecting means of said tubes. 110

In testimony whereof we affix our signatures.

JAMES W. KELCH.
JAMES J. SUNDAY.
